JAMES W. PINKERTON, OF LODI, AND ELMER TOMLINSON, OF STOCKTON, CALIFORNIA;
SAID TOMLINSON ASSIGNOR TO SAID PINKERTON.

DOUBLE-SUCTION CENTRIFUGAL PUMP.

1,352,831.

Specification of Letters Patent. Patented Sept. 14, 1920.

Application filed October 21, 1919. Serial No. 332,346.

To all whom it may concern:

Be it known that we, JAMES W. PINKERTON, a citizen of the United States, residing at Lodi, county of San Joaquin, State of California, and ELMER TOMLINSON, a citizen of the United States, residing at Stockton, county of San Joaquin, State of California, have invented certain new and useful Improvements in Double-Suction Centrifugal Pumps; and we do declare the following to be a full, clear, and exact description of the same, reference being had to the accompanying drawings, and to the characters of reference marked thereon, which form a part of this application.

This invention relates to improvements in centrifugal pumps, the principal object being to provide a pump so constructed that all end thrust will be eliminated, having equal balance at all heads, and which will have a water cushion surrounding the runner at all times.

A further object is to produce a pump which will have very few parts, and which will need very little machining in its manufacture.

These features we attain by providing a water intake on each side of the runner, and by such other construction as will be hereinafter described.

A further object of the invention is to produce a simple and inexpensive device, and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views.

Figure 1 is a longitudinal plan section of the pump.

Fig. 2 is a cross section of the same, taken through the runner.

Fig. 3 is a fragmentary elevation showing the double intake at its outer connecting flange.

Referring now more particularly to the characters of reference on the drawings, the numeral 1 denotes a shaft turnably mounted on bushings 2 fixed in the hubs 3 of the pump casing 4, having a supporting base 4^a, this casing being split along its vertical center line as at 5 and suitably secured together,

in order that the pump runner may be installed therein.

This casing, as is usual practice, is provided with a peripheral cavity or chamber 6, circular in cross section, and increasing in diameter from its inception to the discharge 7.

Secured to the shaft 1 and positioned in the casing is a runner 8, comprising suitably shaped vanes 9 secured to the hub 10, the vanes being inclosed in side walls or webs 11. The vanes and webs however, do not extend to the shaft 1, but terminate short thereof, leaving an orifice 12 on each side of the hub concentric with the shaft for the entrance of the water into the runner. The hub therefore forms a diverting wall for a certain distance from the shaft, sloping away from the shaft substantially to a point, as shown in Fig. 1, so that two channels 13 are formed between the webs of the runner, which channels unite to form one at the termination of the hub. The runner is of course so constructed that these channels shall be of sufficient size relative to the opening 12 that there will be no friction or back pressure caused by attempting to force a body of water through too small an area.

The outer sides of the walls 11 do not fit closely in the casing, but leave a space 14, so that a certain amount of water may fill the space therebetween and form a water cushion. The peripheries of the runner webs however have only a small space between the same and the walls of the casing, the latter adjacent the chamber 6 overlapping the edges of the runner, and being close thereto, as shown at 15 in Fig. 1.

The inner ends of the runner webs are closely alined with the casing at an angle of 45 degrees toward the center, as shown at 16 in Fig. 1, this construction having been found to cause the least water friction and pressure at that point.

The casing 1 between the runner and the bushing 2 is provided with a chamber 17 surrounding the shaft 1, equal in diameter to the runner orifice 12. This chamber communicates with intakes 18, there being one on either side of the runner.

From the chamber 17 these intakes converge and terminate at a common flange 19 beyond the outer periphery of the casing 4, so that one intake pipe may be connected thereto.

105

110

Each of these intakes is formed integral with one of the halves of the casing 4.

Beyond one of the bushings 2 is a packing gland 20, through which the shaft 1 projects to enable it to be connected to a source of turning power, while the other end of the shaft terminates in that bushing, the hub 3 at that end being provided with an air tight cap 21, so that even with no packing gland 10 at that end, air cannot leak therethrough to impede the suction of the pump.

In the operation of the pump it will be evident that the water will be drawn into the runner equally from both sides, on account of the double intake. Also, the two separate columns of water will press with equal force on the interior walls and sides of the hub, centralizing the runner in the casing at all times, and thus giving equal 15 balance at all speeds and heads of water, and eliminating end thrust.

This feature of equal balance is aided by the permanent water cushion had between the runner webs and the casing on the sides 20 thereof.

On account of the fact that the runner will always be perfectly balanced, we are able to assemble the parts with but very little machining being necessary, since the 25 runner will never contact with the casing at any point when once running.

By splitting the casing vertically instead of horizontally we not only obtain a stronger construction and more rigid bearing for the shaft, by reason of the solid bored hubs 30 possible, but may adjust the side distance between the runner and the casing by placing gaskets of different thicknesses between the split portions of the casing.

From the foregoing description it will be readily seen that we have produced such a device as substantially fulfills the object of the invention as set forth herein.

While this specification sets forth in de-

tail the present and preferred construction 45 of the device, still in practice such deviations from such detail may be resorted to as do not form a departure from the spirit of the invention, as defined by the appended claims.

Having thus described our invention what 50 we claim as new and useful and desire to secure by Letters Patent is:—

1. A centrifugal pump comprising a casing, a shaft turnable therein and having a hub thereon and a runner secured on the 55 hub, the runner comprising vanes and having spaced webs connecting the side edges of the vanes and spaced from the walls of the casing, the casing being split transversely of the shaft and centrally of the runner, whereby gaskets may be placed between the adjacent split edges of the casing to alter the distance between the same and the walls of the runner.

2. A centrifugal pump comprising a cas- 60 ing, a shaft turnably mounted therein, a runner on the shaft, said runner including vanes, and spaced webs joining the side edges thereof; and a central chamber surrounding the shaft extending on both sides 70 of the runner and adapted to receive a flow of water thereinto at both ends; the sides of the webs being spaced from the casing to form a water cushion therebetween, and the casing and webs adjacent the chamber 75 being at an opposed angle to the shaft relative to the direction of the flow of water into the central chamber, whereby the water friction and pressure at those points will be reduced to a minimum.

In testimony whereof we affix our signatures in presence of two witnesses.

JAMES W. PINKERTON.
ELMER TOMLINSON.
